UNITED STATES PATENT OFFICE.

PAUL F. SHUEY, OF PITTSBURGH, PENNSYLVANIA.

RADIO SYSTEM.

Application filed November 10, 1922. Serial No. 600,057.

My invention relates broadly to radio systems, and more particularly to radio receiving systems employing a plurality of telephone receivers or loud speakers or both.

5 The object of this invention is to provide a radio receiving apparatus, such, for example, as a standard receiving set, with an indefinite number of telephone receivers or loud speakers or both in excess of the number hitherto regarded as satisfactory or feasible. By my invention I have successfully used considerably more than one hundred telephone receivers on a single standard radio receiving set. My improved system is 10 well adapted to furnish individual beds, rooms, apartments and the like in hospitals, hotels or apartment houses or the like with radio service from a single receiving set. This object may be carried out by many 15 modifications of my system, the accompanying drawings showing only a few of such modifications.

Referring to the accompanying drawings Fig. 1 is a diagram showing a portion of a 20 radio receiving system containing one embodiment of my invention. Figs. 2, 3 and 4 are diagrams showing modifications of portions of Fig. 1.

Referring first to Fig. 1, 1 designates the 25 final electron tube, such as the final amplifying tube, of a radio receiving set, this tube having the usual plate 2, the filament 3, and the grid 4, the connections of the latter two not being shown, as they are well known. 30 I show the A battery 5 and the B battery 6 connected in series, the A battery having the leads 7 and 8 for furnishing current for heating the filaments of the detector and amplifying tubes in a manner well known, 35 the point 9 being a connecting point between the two batteries.

10 is an amplifying transformer of the power or other type for additional amplification. Its primary winding 11 has one 40 terminal connected to the positive end of the B battery and its other terminal connected by one branch wire 12 to the plate 2 and by another branch 13 to one terminal of the primary winding 14 of the transformer 15, the latter branch containing the condenser 16. The remaining terminal of the primary winding 14 is connected by the wire 17 in common with one terminal of the primary winding 18 of the transformer 19 by the 45 wire 20 which may be connected to the posi-

tive pole of the B battery 6 at 21, to the point 9 at 22, or to the negative pole of the A battery 5 at 23 either directly or through the electromagnetic switch 24, operated by the winding 25 having one end connected to 50 the last named battery pole and its remaining end connected by the wire 26 to the top springs 27 of the multiple jacks 28. The remaining terminal of the transformer winding 18 is connected through the condenser 29 to the plate 30 of the amplifying tube 31. 55 33 is a choke coil connected at one end to a point between the condenser 29 and the plate 30, and at the other end to a point between the battery 6 and the transformer winding 11.

The secondary winding 34 of the transformer 15 has its terminals connected by the wires 35 and 36 to the opposite ends of a group 37 of telephone receivers 38. The 60 group 39 of receivers 38 may be connected across the wires 35 and 36 in parallel with the group 37. The condenser 40 may be included in the wire 35 to prevent the flow of direct current, if any, on the wire, or to vary 65 the output impedance to the receivers; and the telephone transmitter or microphone 41 may be connected to the negative pole of the battery 5 and to the wire 35, as shown, so that the operator of the radio set may 70 make announcements to those listening in at any of the receivers 38.

The secondary winding 42 of the transformer 19 has one terminal connected through the condenser 43 to one terminal of 75 each of the loud speakers 44, the other loud speaker terminals being connected to the rings 45 of the jacks 28. The springs 46 in line with the rings 45 are connected to multiple to the wire 47 which is connected to 80 the remaining terminal of the secondary winding 42 of the transformer 19, while the contacts 48 carried by the springs 46, but insulated therefrom, are connected in multiple to the wire 49 which is electrically connected to the point 9, the latter being also electrically connected by the wire 50 to the wire 36 to supply current for the transmitter 41. The open circuited wires leading to the 85 right of the jacks 28 indicates extensions for 90 connection of additional jacks.

For best results the primary impedance of the transformer 10 equals the output impedance of the tube 1 or its associated circuit, and the secondary impedance of the 95 110

transformer 15 or of the transformer 15 and condenser 40 equals the impedance of the circuit or circuits which contain the translating devices, comprising the receivers or loud speakers or both. The impedance of the secondary 34 of the transformer 15 being ascertained, the receivers 38 in the groups 37 and 39 are to be arranged in such relations, as, series, parallel, or series-parallel, 10 that the impedance they insert in the output or secondary circuit shall for best results equal or approximate the secondary impedance. Accordingly, some of the receivers may be placed in series-parallel relation, as 15 in the sections 51 of the groups 37 and 39, and some may be placed in parallel relation, as in the sections 52. The sections may be connected in series in each group, as shown, 20 and the groups placed in parallel, as shown, or the sections may be placed in parallel, or partly in parallel and partly in series, and the groups may be arranged in series, or partly in series and partly in parallel. The drawings and the foregoing description are 25 merely illustrations of methods of arranging the receivers to get the best results from the receivers 38. The person skilled in the art can readily determine from the requirements of an installation the characteristics of the 30 transformer 15 and then can decide upon a grouping and arrangement of the receivers that will give the best results. Of course, results more or less approximating those obtainable by balancing the impedances as 35 described can be secured when the balancing is not departed from to too great a degree. This invention extends to systems wherein the perfect balancing is not departed from to such a degree as to render reception unsatisfactory or impracticable.

The placing of one receiver across the terminals of the secondary of a transformer inserts in the secondary circuit a certain impedance. If a second receiver be placed in 45 series with the first the inserted impedance is doubled, but if the second receiver is placed in parallel with the first the inserted impedance is halved. If, however, the two receivers be connected in series across the 50 secondary terminals and additional third and fourth receivers connected in series be also placed in parallel with the first and second receivers, the impedance due to the receivers will be approximately that due to the first receiver when it was employed alone. The impedance due to one receiver can be approximated by making the number 55 of receivers in each series and the number of series arranged in parallel equal to the square root of the number of receivers used. Where the number of receivers are not perfect squares, the arrangement just defined can be approximated. The principle of balancing the impedance by offsetting inserted 60 series elements by inserted parallel elements,

or vice versa, may be utilized in numerous arrangements. The design of the transformer, or of the transformer and condenser may be so chosen that the secondary impedance approximates a parallel or a series or 70 combined grouping of a certain number of receivers. Then additional receivers may be added by grouping them to suit the transformer impedance.

In the claims the word receivers is used 75 to include telephone receivers, or loud speakers, or both.

The loud speakers 44 may be connected in circuit by inserting a plug in any of the jacks 28, each plug being, of course, operatively connected to one of the loud speakers 44 in the usual manner, not shown. The insertion of a plug into a jack directly connects in the usual manner a ring 45 and a spring 46 in series with the loud speaker, 85 and indirectly connects a contact 48 to a spring 27, the latter connection placing the magnet winding 25 in circuit with the battery 5 through the wires 26 and 49. The current in the winding 25 causes the switch 90 24 to close automatically the circuit of the wires 7 and 8 for heating the various amplifying and detector tubes. Of course, the loud speakers could be left in permanent operating circuit, if desired, thereby allowing the switch 24 and its operating circuit to be left off, the wire 8 then being connected to the battery 5 directly or as desired.

In computing the impedance desired in the output circuit of the secondary 42 of the transformer 19, the same considerations 100 will obtain as for the output circuit of the transformer 15.

For any step of amplification, the system 105 may or may not employ the high impedance winding or choke 33 to by-pass the battery current to the plate 30, in conjunction with the condenser 29 to allow the audio-frequency current to pass through the primary of the transformer and through the plate 30. If 110 this choke and condenser are not used the transformer primary 18 is connected in series with the plate 30 of the tube 31. If they are used, the terminal of the primary winding 115 18 farthest from the plate 30 may be connected by the wire 20 to either terminal of either battery 5 or 6. The primary, as 11, of one or more of the amplifying transformers of the set may be used as an audio-frequency choke to by-pass a portion of the 120 audio current, as between the plate 2 and the primary 14, the remainder of the current passing through the amplifying transformer, as 10, for further amplification, as 125 by the transformer 19, when both receivers 38 and loud speakers 44 are to be used.

The additional amplification required for the loud speaker portion of the system may be obtained as just described or by additional amplifier units of ordinary or power 130

amplification type, by placing the primary, as 11, of the amplifying transformer in series with the primary, as 14, of the telephone receiver system, as shown in Fig. 2.

- 5 Referring now to Fig. 3, I may use, as an alternate circuit when the choke 33 and the condenser 29 are used, the group of receivers 38 or loud speakers 44, which may be connected in series with the primary, as 18, of the receiver system transformer in such a manner that the polarity of the secondary winding 42 is such that its effect on the receivers is additive to that impressed directly on them through the primary winding 18.
- 10 The transmitter 41 may be used for the purpose for which it is used in Fig. 1.
- When it is desired to use only a few loud speakers 44 with receivers 38, the amplifying means shown for the loud speakers are omitted or disconnected from the system, as at the points 54 and 55, and the wires to the right of these points are respectively connected to the points 56 and 57, respectively in the wire 17, the portion of the latter between the latter points being omitted or open circuited, I show in Fig. 4 the modification just described. The separate sections 51 and 52 or their equivalents may be placed in different wards, wings, or sections of hospitals or other buildings, or in different buildings. The chances are that the persons in the several sections will act similarly, so that the system will continue to be in fairly good balance, although the number of receivers may be constantly changing.

I claim—

1. In a radio receiving system a relatively large number of receiving elements, and a transformer having the said receivers in circuit therewith, the receivers being grouped in series and parallel relations to make the impedance they impose in the circuit approximate that of the secondary of the transformer. 40
2. In a signal-reproducing system adapted to serve a plurality of persons, a plurality of groups of translating devices, each group being located in a place frequented by a different portion of said plurality of persons, a line connecting said groups in parallel, and a signal-delivering device connected to said line, the places for the groups being so selected that the probability of the number of translating devices in the respective groups in use at the same time being approximately equal will be great. 45
3. In a vacuum-tube, signal-reproducing system, a vacuum-tube amplifier, translating devices connected to the output thereof, other translating devices requiring greater energy than the first mentioned translating devices, a second amplifier having its input connected to the output of the first mentioned amplifier and its output to said other translating devices and means actuated upon the closing of the connection to said other translating devices for rendering said second amplifier active. 55

In testimony whereof, I affix my signature.
PAUL F. SHUEY.
